METHOD OF AND AN APPARATUS FOR
CHARGING CELLULOSE DIGESTERS
OR THE LIKE

Sjune Svensson, Hissmofors, Krokom, Sweden

Application October 27, 1934, Serial No. 750,378
In Sweden May 27, 1933

10 Claims. (Cl. 92—7)

By means of the method described in the U. S. Patent No. 1,539,147 for charging cellulose digesters by means of steam which is forced into them considerable advantages have been obtained. Yet it has proved that under certain circumstances, for example, when the charge material is very dry, at quick filling, in using a high steam pressure etc., air accompanies the charge material down into the digester and during the filling operation effects such a high over-pressure in the same that drawbacks arise.

The present invention relates to a method and an apparatus, by which the said drawbacks are overcome, and consists substantially in introducing into the downwardly flowing fibrous material before subjecting the same to the action of the current or currents of steam increasing the speed of the fibrous material, either the entire quantity or part of the excess steam assembling in the digester during the charging operation.

The excess steam from the digester may be introduced into the charge material in such direction that it has no entraining action upon the downwardly flowing material.

It has proved to be advantageous to introduce the excess steam into the downwardly flowing charge material in such a quantity that the steam completely or in part prevents the air accompanying the charge material from getting into the digester.

The charge material may preferably be introduced into the digester through a pipe disposed in the upper portion of the digester, the excess steam being supplied to the charge material, while the latter passes this inlet pipe. The supplied excess steam is condensed in part in the charge material and an advantageous preliminary steaming is obtained thereby.

The accompanying drawing illustrates embodiments of an apparatus for carrying out the method according to the invention.

Figures 1, 3 and 5 are vertical sections of the apparatus and

Figures 2, 4 and 6 are horizontal views of the apparatus shown in Figures 1 and 3, 5 respectively.

Figure 7 shows an apparatus connected to a digester.

The same reference numerals refer to members having the same function in the various embodiments.

In the embodiment shown in Figures 1 and 2 numeral 1 indicates the main conduit, from which the steam is taken to the apparatus.

Through the conduit 2 the steam is conducted to an annular collecting chamber 3, from which nozzles 4 open slantingly downwards into a cylinder 5 disposed below the collecting chamber. The charge material is supplied to the digester through the cylinder 6 and passes through a further cylinder 7 and through the cylinder 5 down into the digester. The cylinder 6 is slidably disposed in vertical direction by means of the spindles 8, so that an opening 9 may be obtained between the cylinders 6 and 7. The disk 10 is secured in and tightens against the upper plane of the neck of the digester and supports the apparatus.

When the charge material flows down into the digester, it is spread and packed in the same by means of steam leaving through the nozzles 4. When the pressure in the digester has become sufficiently high excess steam will flow through the opening located between the cylinders 6 and 7 and be mixed with the charge material. The pressure in the digester is controlled by making the opening 9 larger or smaller. The steam is preferably supplied to the charge material through the opening 9 in such a quantity that air accompanying the charge material is prevented from getting into the digester.

The embodiment shown in Figures 3 and 4 differs from the one above described substantially in that the opening 9 has been replaced by a number of openings 11 provided in the cylinder 6. The size of the said openings 11 is controlled by a cylindrical portion 12 disposed around the cylinder and by means of which the spindles 13 may be pushed over the openings 11.

In the apparatus shown in Figures 5 and 6 the steam is conducted through the pipe 2 to an annular collecting chamber 3, located around the upper portion of the apparatus. Steam pipes 14 lead from the collecting chamber to the nozzles 4, through which the steam flows out into the cylinder 5, the material flowing down through the cylinder 6 being entrained. The opening 9 is controlled in the same manner as in the apparatus shown in Figures 1 and 2, viz. by sliding the cylinder 6 in vertical direction by means of the spindles 8. Reference numeral 10 indicates the same disk as in the preceding embodiments of the apparatus.

In Figure 7 numeral 15 indicates the digester in the neck of which the apparatus is disposed. The charge material is supplied to the digester 15 through the funnel 16 and the cylinder 6 and the steam is supplied through the conduit 2 down

to the annular collecting chamber 3, from which nozzles open slantingly downwards into a cylinder 5 in the same manner as shown in Figures 1, 3 and 5. To control the opening 9 between the cylinders 6 and 7 a damper 17 in the shape of an annular strip is disposed about the lower portion of the cylinder 6. The ends of the strip are united by means of screws 18 for tightening the strip about the cylinder 6 in the various adjusting positions of the strip.

The openings 9 and 11 must not necessarily be adapted to be controlled. They may also be of a certain fixed size adapted to the pressure, which is intended to prevail in the digester during the charging operation. The said pressure should be an overpressure of at most 250 mm. water column.

The invention is not restricted to the charging of cellulose digesters but may be used also for other similar purposes.

Having now described my invention, what I claim as new and desire to secure by Letters Patent is:

1. In a method of charging cellulose digesters with fibrous material, for instance, chip wood, in which the speed of the charging material is accelerated only by means of steam, introducing excess steam, assembled in the digester during the charging operation, into the downwardly flowing charging material before the same is subjected to actuation by the speed accelerating steam, in such direction that it has no entraining effect upon the charging material and in such a quantity that the excess steam prevents air accompanying the charging material from getting into the digester.

2. In a method of charging cellulose digesters with fibrous material, for instance, chip wood, using steam only as speed accelerating means, introducing the charging material into the digester through an inlet in the upper portion of the digester and introducing excess steam, assembled in the digester during the charging operation, into the downwardly flowing charging material, before the same is subjected to actuation by the speed accelerating steam, through at least one opening provided in said inlet.

3. In a method according to claim 2, control-

ling the quantity of introduced excess steam in the inlet by means of regulating the dimension of the inlet opening.

4. An arrangement in cellulose digesters and the like, in which there are provided in the upper portion of the digester a filling pipe for introducing the charging material, the said pipe being provided with at least one possibly controllable opening for introducing excess steam from the digester, and nozzles disposed below the said openings and serving to introduce steam, which is to have an entraining action upon the material.

5. Arrangement according to claim 4, in which an annular steam pipe is disposed outside the filling pipe and connected with the nozzles for the introduction of steam.

6. Arrangement according to claim 4, in which the filling pipe comprises two cylindrical parts one located above the other, through which the fibrous material flows down into the digester, the interspace between the cylindrical parts forming the opening for introducing excess steam.

7. An arrangement in cellulose digesters, in which there are provided in the upper portion of the digester two cylindrical parts one located above the other, through which the fibrous material flows down into the digester, the interspace between the cylindrical parts forming an opening for introducing excess steam from the digester, and nozzles disposed below said interspace and serving to introduce steam which is to have an entraining action upon the material.

8. Arrangement according to claim 7, in which the lower part of the filling pipe is widened below the nozzles, preferably by means of a cylindrical portion having a larger diameter than the diameter of the portion where the nozzles are located.

9. Arrangement according to claim 7, in which the upper part of the filling pipe is slideable so as to control the size of the opening between the two parts through which the excess steam is supplied.

10. Arrangement according to claim 7 in which the upper part of the filling pipe by means of adjusting devices is adapted to be raised or lowered during the charging operation.

SJUNE SVENSSON.
